METHOD OF MANUFACTURING INFUSION
PACKAGES

Hans O. Irmscher, East Hempstead, Long Island,
N. Y., assignor to National Urn Bag Co., Inc.,
Long Island City, N. Y., a corporation of New
York

Application October 14, 1942, Serial No. 461,963

5 Claims. (Cl. 93—3)

1

This invention relates to the manufacture of filled containers or bags, and more particularly is directed to infusion packages, such as tea-balls with handles and like articles of manufacture.

Among the objects of the invention is to generally improve the construction of filled containers or bags in the form of infusion packages with handles as inexpensive articles of manufacture, which shall comprise few and simple parts, which shall be easy and cheap to manufacture, which shall be capable of quantity production on automatic super high-speed packaging machines, which shall have pressure heat sealed joint seams forming an improved attachment connection of a string handle with the bag portion of each package, and which shall be practical and efficient to a high degree in use.

Other objects of the invention will in part be obvious and in part hereinafter pointed out. The invention accordingly consists of features of constructions, combinations of elements, arrangements of parts which will be exemplified in the constructions and method hereinafter described and of which the scope of the application will be indicated in the following claims.

In the accompanying drawing in which are shown various possible illustrative embodiments of this invention.

Fig. 1 is a view showing a method embodying the invention as applied to the manufacture of tea-balls.

Fig. 2 is a view as seen from lines 2—2 in Fig. 1.

Fig. 3 is a front elevational view of a completely manufactured tea-ball and string handle embodying the invention.

Fig. 4 is a cross sectional view taken on lines 4—4 in Fig. 3.

Fig. 5 is a view showing a variation of the improved method of manufacturing tea-balls embodying the invention, and

Figs. 6 and 7 are sectional views taken on lines 6—6 and 7—7, respectively, in Fig. 5.

Referring in detail to the drawing, 10 denotes a tea-ball completely manufactured and constructed to embody the invention.

In practising the embodiment of the invention shown in Figs. 1 to 4 inclusive, heat sealing sheet material 11 may be used in making a bag 10a of said tea-ball 10 in which the contents T is enclosed. Said heat sealing sheet material 11 may be of any suitable foraminous construction, such as filter paper, finely perforated parchment or Cellophane, cotton gauze and the like layer base treated or coated with a dry thermosetting plastic

2

lamina. Where filter paper is used as sheet material 11, the base layer is made of vegetable fibrous pulp stock which is coated with the dry porous lamina, so that when made into tea-ball 10a has sufficient wet strength to withstand immersion in boiling water without damage or disintegration and without loss of tensile strength. Bags 10a of tea-balls 10 made of said filter sheet material 11 permits ready infusion and must have such composition that it is insoluble in hot water, produces no toxic effects, and imparts no odor or taste even to the slightest degree to the brew.

The bag 10a of the tea-ball 10 for economy

15 may be produced on a super high output tea-ball manufacturing machine such as described and shown in applicant's copending application, Ser. No. 450,289, filed July 9, 1942, for Infusion package manufacture, and may comprise mate-

20 rials assembled and heat sealed as shown and described in said applicant's aforementioned application with the addition of providing a string handle 12 in the manner hereinafter set forth.

When coated filter paper is used as sheet ma-

25 terial 11, it has been found in practice that a 6½ pound fibrous stock sheet of approximately .001 inch thick of high wet tensile strength forms a practical filter paper base layer for the pur-

30 poses described herein. On such layer finely powdered copolymer of vinyl chloride and vinyl acetate may be uniformly sprinkled or sprayed,

“partially fused” by heat to 60° C., and pressure rolled thereon for providing a pervious, dry and extremely thin coating or lamina which does not 35 materially affect the filtering capacity of said layer. Approximately three ounces of such vinyl powder for each pound of said layer will form a porous coating or lamina of normally less than .0005 inch thick.

40 Tea-ball bags 10a when constructed of the aforementioned sheet material 11 have the lamina or coating side of the filter material 11 as the interior surface of the tea-ball bag 10a. The edge seam joints 10b and top seam closure

45 10c of said bag 10a for enclosing the contents T are then formed by having the coating surfaces placed in face to face relation, pressure heat sealed into permanent adhesion. With said coat-

50 ings formed of copolymer of vinyl chloride and vinyl acetate permanent sealing fusion of said joints 10b and closure 10c will take place when pressure heat sealed at about 130° C.

The present invention is directed particularly to the manufacture of tea-balls 10 with permanently attached string handles. When coated

heat sealing filter sheet material 11 is used in machines such as described in my said copending application, Ser. No. 450,289, such sheet material 11 is fed from a suitable supply as a continuous strip or web and while continuously travelling through is folded centrally thereof to provide a longitudinally extending bottom fold 10d. Said web while being folded is engaged by a series of spaced movable pincer jaws, indicated in Figs. 1 and 2 in dotted lines at J to provide section units which are filled with uniform quantities of tea T by suitable measuring device (not shown) in any well understood manner through the top openings of the bags before the same are heat sealed. Said bag top openings of the section units are then permanently heat sealed as at closure 10c, spaces S being left unsealed between each of said section units.

To provide a string handle for each unit section in practising the invention, a continuous length of string is formed into sinusoid or wave-like configuration having a series of looped handle portion 12 alternately disposed with relation to a series of bights 12a by means of suitable spaced pins P, so constructed and arranged as to engage one or more of string portion forming said bights 12a, the latter being inserted into the moving folded web through the unsealed portions S at the top openings of the unit sections, as shown in Figs. 1 and 2. The successive bights 12a remain in their inserted position between the unit section of folded web when the pins P are withdrawn. Then suitable pressure heat sealing means (not shown) are applied in any well understood manner to permanently heat seal partition joints 10e between the unit section thereby embedding the portions of the string forming the bights 12a therein all while the filled unit section formed from said web is kept moving or travelling through machine. One or more of the leading section units are then severed from the leading end of such travelling web by a suitable knife or cutter K so as to leave complete individual tea-balls 10 with attached string bail handles 12 as shown in Fig. 1.

It is to be understood that the portions of the string handle forming the bights 12a embedded into the heat sealed partition joints 10e may extend any suitable distance within said sealed partition joints in order to assure positive attachment anchorage. As shown in Figs. 1 and 3, the portions forming the bights 12a extend through a great part of the length of the partition joints 10e, the bights 12a and the partition joint 10e being severed by the cutter K centrally at their midportion leaving the edge joints seal at 10b intact. The portion of the strings embedded in each of the severed joints 10b is formed of a semi-bight 12a which extends to the edge of the joint 10b. Preferably the surfaces of heat sealed partition joints 10e and closure 10c may be corrugated as shown to increase the bondages of said joints and improve the appearance of the finished tea-balls 10. The bail handle 12 provided on each tea-ball 10 is non-tangling to facilitate packing for shipment and for dispensing when used, and requires no alteration in the tea-ball structure by the user for making the suspension package handle available for the brewing operation.

Where the invention is practised in connection with other forms of high speed tea-ball making machines such as those operating, as for example, as shown in Figs. 5, 6 and 7 where the travelling folded web is first heat sealed with the spaced partition joints 10e forming successive unit sections which are filled with the tea or the like T

before the top sealed closures 10c are applied, the string handle 12 is formed into the sinusoid or wave-like configuration in the same manner as described above, while the unit sections are being formed and filled, and the bights 12a are inserted only to a depth to the top ends of partitions joints 10e after which the top closures are heat sealed with joints 10c permanently anchoring the bight portions of the string handle. Thereafter, one or more leading sealed section units, each with a handle 12 may be severed from the moving web for providing the tea-ball 10 with a string bail handle 12.

It is thus therefore seen that there is provided an improved method of manufacture and an article in which the objects of the invention are achieved and which are well adapted to meet all conditions of practical use.

As various possible embodiments may be made in the above invention and as various changes might be made in the embodiments and method above set forth, it is understood that all the above matters here set forth or shown in the accompanying drawing are to be interpreted as illustrative and not in a limiting sense.

Thus having described my invention, I claim as new and desire to secure by Letters Patent:

1. In a method of manufacturing of the character described, the steps of continuously moving and folding a strip of heat sealing bag sheet material to form spaced apart filled section units with closed bottoms, arranging a string in wave-like configuration with alternate loop and bight portions, inserting said bight portions into the sheet material between the section units, heat sealing said sheet material about each section unit for permanently embedding the inserted string bight portions in seam joint portions between said section units, and severing said seam joint and the bight string portions embedded therein centrally for completing successive individual packages each with loop string handle portion having the ends thereof permanently anchored in oppositely positioned heat sealed joints of each package to provide a bail handle.

2. The method as defined in claim 1 in which said steps of arranging the string and inserting the bight portions are carried out concurrently with the steps of forming the filled section units.

3. In the method of manufacturing packages formed with spaced heat sealed seam joints, the steps of arranging a string with alternate loop and bight portions in wave-like configuration, inserting the string bight portions within successive joints prior to the heat sealing thereof, heat sealing and severing the heat sealed joint and each bight portion to form a bail handle of said string loop portions with a split bight portion anchored in a split portion of the heat sealed joints on individual packages cut off by the severing operation.

4. In a method of the character described, the steps of making a series of connecting bags formed with heat sealed seam side joints of uniform width extending thereabout, filling said bags, arranging in wavelike configuration a string with relatively large loops and narrower bight portions spaced therebetween, inserting the spaced bight portions of said arranged string in position between the bags, and heat sealing a top closure seam joint to incorporate said bight portions for permanently anchoring same, and splitting said side joints centrally to provide a looped bail handle extending across the width and be-

yond each bag a sufficient distance to serve as a finger gripping means.

5. A method of making tea-balls which comprises placing heat sealing filter paper in face to face relation and forming a series of section units of bags having uniformly spaced joints with a charge of tea in each bag unit between said joints, arranging a string in wave-like configuration with alternate loops and bights so that the loops extend beyond the bag units a sufficient distance to provide a finger gripping means and the bights inserted in position between said units in said joints

short of the length thereof, heat sealing said joints to embed the bights in said position, and splitting said last mentioned seam joints centrally along a length of each and cutting the embedded bights to terminate each in a curved end at the edge of said seam joint leaving the closure thereat intact with said curved ends of the cut bights permanently anchored in successive split seam joints to provide a succession of tea-balls with tagless bail handles.

HANS O. IRMSCHER.
